GRINDING WHEEL TRUING MECHANISM

Lee M. Davis, Springfield, Vt., assignor to Jones & Lamson Machine Company, Springfield, Vt., a corporation of Vermont

Application July 12, 1941, Serial No. 402,058

4 Claims. (Cl. 125—11)

In the Flanders Patent No. 2,184,011, for Grinding machine, granted December 19, 1939, is shown a mechanism for truing grinding wheels for cutting screw threads but when threads having considerable lead are to be ground, a greater truing tool traverse than can be obtained by the mechanism shown in that patent is necessary.

An object of this invention, therefore, is to provide a truing mechanism by which such increased traverse is obtainable.

For a more complete understanding of this invention, together with further objects and advantageous constructions, reference may be had to the accompanying drawings in which

Figure 1 is a front end elevation of the mechanism with certain parts omitted.

Figures 2, 3, 6 and 10 are sectional views, Figures 3, 6 and 10 being fragmentary, on the correspondingly numbered section lines of Figure 1, the section line for Figure 10 also appearing on Figure 3.

Figure 4 is a detail sectional view on line 4—4 of Figure 3.

Figure 5 is a detail sectional view on line 5—5 of Figure 2.

Figure 7 is a view similar to Figure 6, but showing the side truing devices at the opposite limits of motion.

Figure 8 is a detail sectional view to a larger scale on line 8—8 of Figure 6.

Figure 9 is a detail sectional view on line 9—9 of Figure 5.

Figure 11 is a sectional view on line 11—11 of Figure 2.

Figure 12 is a fragmentary perspective view showing a side truing device cam and its mounting.

Figures 13 and 14 are end and side elevations, respectively, to a larger scale, of a cam member.

Figure 15 is a development of the cam of Figures 13 and 14.

Referring to the drawings, at 1 is indicated a tubular casing carrying the truing mechanism and which may be substituted for the truing mechanism and casing shown in the Flanders Patent No. 2,184,011. This casing 1 is provided with three transverse partitions 2, 3 and 4 between its ends. The partition 2, which is nearest to the grinding wheel, shown at 5 in Figures 6 and 7, is provided with a transverse slot 6 through which may be extended a pair of bars 7, to the forward ends of which outside of the partition 2, are supported truing devices 8. An angle member 9 having a horizontal leg 10 projecting inwardly through the slot 7 and forming with

the base of this slot a guideway for the sliding reception of the bar 7 is provided with a vertical flange 11 which may be adjustably secured to the outer face of the partition 2 as by means of screws 12. This angle member 9 retains the bars 7 down against the lower face of the slot 6.

In order to prevent the entry of foreign matter into the casing through the slot 6, this slot is bridged over by a flexible hood 14 secured to the partition 2 around the slot 6 by the clamping bars 15 and having openings through which the bars 7 project and make close contact with the sides of these bars. These bars 7 are L shaped in plan, being provided at their rear ends with lateral extensions 20 which extend away from each other. The rear ends of these bars thus widened by the extensions 20 have pivoted thereto the forward ends of a pair of links 21, the rear ends of which are in turn pivoted as at 22 to a carriage 23 mounted for rectilinear motion lengthwise of the casing 1 on a pair of guide bars 24 and 25, opposite ends of which are mounted in perforated bosses in the partitions 2 and 3.

The links 21, arranged in pairs, both links of each pair being pivoted to its corresponding bar 7, act together as a parallel motion permitting lateral motion of the bar 7, while restraining these bars 7 to remaining in parallel relation to each other. This is shown best in Figures 6 and 7, the bars 7 being shown in their inner positions in Figure 6 where they are relatively close together, and in their outer positions in Figure 7 where they are shown as projected well through the partition 2. In both views, however, these bars 7 are shown as being maintained in parallel relationship by their double link connections to the carriage 23.

The carriage 23, at one side adjacent to the guide bar 25 is provided with a boss 26 supporting a stub shaft on which is journaled a cam roller 27. This cam roller 27, as shown best in Figures 7 and 10, engages in a cam groove 28 of a barrel cam 29 secured to a rotary shaft 30 positioned between and with its axis slightly above the guide bars 24 and 25. This shaft 30 is arranged to be driven from a motor 31 carried by the casing 1 rearwardly of the partition 4 to the back face of which partition the motor 31 may be secured. The armature shaft 32 of this motor is connected through a coupling 33 to a shaft 34 carrying a worm 35 which meshes with a worm wheel 36 on a vertical shaft 37. This vertical shaft 37 carries near its lower end a worm 38 which meshes with a worm wheel 39 keyed to the shaft 37. This worm and worm wheel drive

connection acts as a reduction gearing, causing the shaft 30 to be rotated at a very much slower speed than the armature shaft 32, such that the shaft 30 rotates once for each truing and return pass of the side truing tools 8, which complete truing pass constitutes a single complete truing cycle. The shaft 30 extends through a cover plate 40 enclosing the rear end of the casing 1 and into a compartment 41 thereof which may contain electric switch mechanism having the controlling functions of the mechanism shown in the Flanders Patent No. 2,184,011 within the casing 210, the shaft 30 herein performing the functions of the shaft 120 shown in the Flanders patent. As in the case of the Flanders patent, this shaft 30 controls presentation of the truing devices to and retractions from the grinding wheel by the rocking back and forth of a threaded shaft 42 having a bearing against the end of a shaft 43 corresponding in function to the shaft 51 of the Flanders Patent No. 2,184,011. As this particular portion of the mechanism forms no part of the present invention, reference may be had to the Flanders Patent No. 2,184,011 for a more complete understanding thereof.

As the bars 7 are moved lengthwise of the casing 1 by the motion of the carriage 23 they are also moved laterally from and toward each other in accordance with the side contour desired for the grinding wheel 5, which is shown herein as shaped to grind screw threads. This lateral motion of the side truing tools is produced by the action of cam mechanism. Such cam mechanism comprises a pair of oppositely disposed reversely faced edge cams 50, each of these cams being supported on an integral bracket portion 51 extending inwardly from the wall of the casing 1. Each of the cams 50 is pivoted, as on the vertical pin 52, to the top face of its bracket 51, and its outer side face may engage against an adjusting stop screw 53 threaded through a bar 54 secured as by screws to the top face of the bracket 51. A locking screw 530 extends through an arcuate slot 531 through the cam 50 and is threaded into the shelf 51. Each of the cam plates 50 has an edge cam face 55 across which may be traversed a follower 56 carried by a post 57 secured to the corresponding bar 7, and the followers 56 are held against their cam faces as by springs 58, each of these springs having one end secured to a bar 7 as at 59 and the opposite end secured to a fixed point 60 of the casing 1. Thus as the carriage 23 is reciprocated, the bars 7 are not only moved in and out, but transversely as well, in paths depending upon the configurations of the cam faces 55.

As shown there is a third wheel truing device 70 carried by an arm 71 fixed to an axially movable and rockable shaft 72. This shaft 72 extends through an opening 73 through the partition 1 and a flexible hood 74 through which the shaft 72 extends and which is secured about its margin to the forward face of the partition 2 around the opening 73 serves to seal this opening against the entry of foreign matter into the casing 1 back of the partition 2. This shaft 72 has a rearward extremity 75 of reduced cross section which extends into a bushing 76 in a bracket portion 77 of the partition 3 in alignment with the shaft 34 which is journaled therein.

The shaft 72 is normally pushed toward its outer axial position as by a spring 80 surrounding the reduced diameter portion 75, one end of which spring bears on a shoulder 81 on the shaft 72 and the other end of which bears against the bushing 76 within which the rear end of the shaft

72 is slidably and rockably mounted. This spring 80 holds a collar 83 secured to the shaft 72, as by a set screw 84, into engagement with the upper end of a lever 85 pinned to a rock shaft 86 back of the partition 2. The lower end of this lever 85 is formed as a cam follower 87 and rides in a groove 88 in the barrel cam 29. This groove 88 on its back face forms a cam 89 which acts, as the shaft 72 rotates, to oscillate the lever 85 and thus produce axial reciprocation of the shaft 72 and consequently of the end truing tool 70. This reciprocatory motion brings the end truing tool into and out of operative relation to the apex 90 of the grinding wheel 5. By oscillatory motion of the shaft 72 this truing tool 70 is caused to traverse across this apex. This oscillatory motion is produced by an edge cam portion 95 of the cam 29 adjacent to the peripheral groove 88, one side wall of which controls the rocking of the lever 85. As shown in Figure 5, this cam portion 95 acts upon a follower portion 96 of a lever 97 having a hub 98 journaled on the guide bar 24. This lever 97 has an arm 99 connected through a link 100 to an arm 101 extending from the block 83.

Connections from the link 100 to the arm 101 and to the arm 98 may be made as shown in Figure 9, allowing a slight universal motion between these parts so as to permit the axial as well as the rocking motion of the shaft 72, while the hub 98 is held against axial motion. The connecting pivots 102 for the ends of the link 100 may each therefore be provided with a spherical enlargement 103 inwardly of a head 104 and the link 100 may be provided with cylindrical sockets 105 at its ends for engagement with the spherical portions 103 of the pins 102.

In order to take up lost motion between the cam 29 and the follower 27 which reciprocates the side bars 7, a friction device has been illustrated. This device comprises a bar 110 secured as by a screw 111 to the rear portion of the carriage 23, this bar extending through a perforation in the partition 3 and through a friction gland 112 carried by the partition 4. As shown best in Figures 3 and 4, this gland comprises a bushing portion 113 seated in an opening through the partition 4 and having a flange 114 overlying the rear face of the partition. Back of this gland 112 there is arranged a pair of blocks 115 and 116, each having an arcuate opening to engage on one side of the bar 110 and to be pressed toward each other to impart frictional drag to axial motion of the bar 110 by a pair of springs 117 surrounding a pair of screws 118. Each of these screws is threaded into the block 116 and has a head 119 within a socket 120 in the block 115 within which one of the springs 117 is positioned, this spring reacting between the base of its socket and the head 119 of the screws. A pair of screws 125 passing through notches 126 in the blocks 115 and 116 and passing through the flange 114 and threaded into the partition 4 secure these blocks 115 and 116 in position.

Each of the side truing devices 8 may be mounted on its bar 7 as shown best in Figure 8. Each device 8 is in the form of a cylindrical rod pointed at its outer end where it holds the cutting point. It is axially slidable through an opening 130 between upper and lower portions of a block 131. This opening may have a V base against the side of which the device 8 is clamped by a set screw 132 and it is backed up by an adjustable plug 133 threaded through a back wall portion 134 of the upper portion of the block 131.

This block has a depending channel shaped portion 135, through the web of which a securing screw 136 threaded into the bar 7 extends.

In operation of this mechanism, rotation of the motor 31 from a rest position at the end of a truing cycle causes the casing 1 to advance toward the wheel and then the bars 7 to be moved from the position of Figure 6 across the side faces of the wheel to the position of Figure 7 and return. During the advance of the side truing tool the edge truing tool is moved axially into operative relation to the apex of the grinding wheel and is rocked to traverse this apex. The apex truing tool is then retracted so as to get out of the way of the side truing tools. The casing as a whole is then retracted by the rotation of the shaft 30 and its action on the threaded shaft 42, and the motor 31 is stopped. This cycle is the same as that of the truing mechanism shown in the Flanders Patent No. 2,184,011, to which reference has heretofore been made. By reason of the mounting of the side truing tools, however, a much greater amplitude of motion suitable for wheels of greater thickness than can be trued by the Flanders mechanism, can be trued by the mechanism of this invention.

From the foregoing description of an embodiment of this invention, it should be evident to those skilled in the art that various changes and modifications might be made without departing from the spirit or scope of this invention as defined by the appended claims.

I claim:

1. A wheel truing mechanism comprising a support, a pair of side truing devices, means on said support for guiding said side truing devices for in and out motion in intersecting paths, an end truing tool mounted on said support for rocking and axial motions, a rotary cam, connections from said cam for rocking said end truing tool, and connections carried by said support from said side truing tools to said end truing tool for moving said end truing tool axially with the in and out motion of said side truing tool.

2. A wheel truing mechanism comprising a pair of side truing devices, means for guiding said side truing devices for in and out motion in intersecting paths, an end truing tool mounted for rocking and axial motions, a rotary cam, connec-

tions from said cam for rocking said end truing tool, and connections from said side truing tools and end truing tool for moving said end truing tool axially with the in and out motion of said side truing tool, said connections including universal pivotal parts facilitating both rocking and axial motion of said end truing tool.

3. A wheel truing mechanism comprising a support, a rock shaft mounted for axial motion in said support, an arm carried by said shaft, a wheel truing device carried by said arm, a rotary shaft journaled in said support substantially parallel to said rock shaft, a cam carried by said rotary shaft and having edge and axial cam faces, a lever having a follower riding on said edge cam face, connections from said lever to said rock shaft for rocking said rock shaft to move said rock shaft across said grinding wheel face by oscillation of said lever, said connections including a universal joint, a follower for said axial cam face, operative connections from said last-mentioned follower to said rock shaft causing axial motion of said rock shaft from said axial cam face to move said device into and out of wheel truing position, and means for rotating said rotary shaft.

4. A wheel truing mechanism comprising a casing, a rock shaft mounted for axial motion in said casing and projecting through a wall of said casing, an arm carried by said shaft outwardly of said wall, a wheel truing device carried by said arm, a rotary shaft journaled in said casing substantially parallel to said rock shaft, a cam carried by said rotary shaft and having a pair of cam faces, a lever having a follower riding on one of said cam faces, connections from said lever to said rock shaft for rocking said rock shaft to move said device across a grinding wheel face by oscillation of said lever, said connections including a universal joint, a follower for the other of said cam faces, operative connections from said last mentioned follower to said rock shaft causing axial motion of said rock shaft by motion of said last mentioned follower from said other cam face to move said device into and out of wheel truing position, and means for rotating said rotary shaft.

LEE M. DAVIS.
